HAMMER HEAD

Andrew F. Bianchini, Providence, R.I., assignor to Industrial Tool & Machine Co., Georgiaville, R.I., a corporation of Rhode Island

Filed Mar. 2, 1966, Ser. No. 1,242

Term of patent 3½ years

(Cl. D93—4)

FIG. 1

FIG. 2

FIG. 3

FIG. 4

FIG. 5

FIG. 1 is a side elevation of a hammer head embodying my new design.

FIG. 2 is a front elevation thereof.

FIG. 3 is a rear elevation thereof.

FIG. 4 is a top plan view thereof.

FIG. 5 is a bottom plan view thereof.

The partial broken line showing of the handle in FIGS. 1, 2 and 3 is for illustrative purposes only.

I claim:

The ornamental design for a hammer head, as shown and described.
